ENDLESS CHAIN BALLAST REMOVING
APPARATUSJoseph M. Fox, Havertown, and Clarence J. Reigh,
Altoona, Pa.

Application June 14, 1948, Serial No. 32,795

10 Claims. (Cl. 37—104)

1

Our invention has reference to means for removing materials such as broken stone, cinder, slag, gravel and dirt comprising the ballast in track, which has become fouled and interferes with the proper drainage of the track structure, from the cribs between ties of a track, to approximately the bottom of ties.

This material is deposited in the intertrack space or on the border where it can be cleaned by one of the existing machines used for such purposes, and returned to the tie cribs, or if wasting of the fouled ballast is desired, it can be disposed of by loading or shoveling out on the track shoulder and be replaced by new ballast.

It further materially assists in the renewal or spacing of ties by clearing the cribs between ties of ballast and allowing free movement of the tie laterally.

Cribbing apparatus or machines as known are invariably cumbersome to handle, as well as difficult to remove from, and place back on a railroad track owing to their excessive weight and the resultant need for switching the same into a siding to clear the track and permit passenger or freight trains to pass, or when working on outside tracks clearing on a prepared set-off, clear of all tracks, when the machines are designed to make this possible.

A primary object of our invention, accordingly, is to overcome the above noted disadvantages by providing a cribbing machine or unit which can be transported along a railroad track, readily removed therefrom into the track interspace; and just as expeditiously replaced on the track rails without the necessity of running to a siding, to afford right of way for oncoming trains, or clearing machine on a prepared set-off.

Another object is to provide a cribbing machine or unit which will effectively remove the inter-tie ballast from the crib to the desired side of the railroad.

A further object of our invention is to provide a track cribbing machine capable of individual use, or of being serially assembled for collective or serial operation.

A still further object of our invention is to provide a machine of the type above indicated including an endless and easily detachable drag device capable of quickly clearing out the cribs of railroad track and ejecting the removed ballast to the desired side of the track.

A further important object is the provision of a self-propelled cribbing machine for the removal of railroad ballast, which is simple in construction, comparatively cheap to manufac-

ture and much lighter in weight than similar means heretofore available.

In the accompanying drawings:

Fig. 1 is a plan view of a typical embodiment of our improved cribbing machine.

Fig. 2 is a side elevation of the same, viewed from below the preceding figure and showing said machine in active position.

Fig. 3 is a somewhat similar view, to the preceding figure but showing the machine as it completes or finishes the crib clearing operative cycle.

Fig. 4 is an end elevation looking from the right hand towards the left of Fig. 3; and

Fig. 5 is a side elevation of the machine with the drag means removed, as hereinafter fully described.

In describing the form of this invention, exemplified in the drawings herewith, specific terms will be employed for the sake of clarity, but it is to be understood the scope of said invention is not thereby limited; each such term being intended to embrace all equivalents which perform the same function for an analogous purpose.

Referring more in detail to the drawings, the complete machine typified comprises a truck comprehensively designated 1, mounted on flanged wheels 2, 2', and capable of operation for progression along the track rails 3 by means of appropriate driving mechanism, hereinafter explained, from a suitable air-cooled motor for example only such as indicated by the dot-and-dash rectangle 4 in Fig. 1, such means being well known and needing no further illustration or explanation herein.

The truck 1 conveniently consists of a rectangular frame 5 from which, and spaced from the ends thereof depend pairs of bearing members 6 that include appropriate stub-axles 8 for the front flanged track wheels 2, whereas the rear track wheels 2' are mounted on short trunnions 9 in the spaced bearing members 6, see Figs. 2-5, and both of said members 6 are dependently secured to the bottom of the rear and front components of the rectangular frame 5. The trunnions 9 are preferably coupled by through pins 10 engaged in the open end slots 11 of a hollow shaft 12, fitted with a rigidly attached gear 13 capable of being selectively meshed by either of a pair of rotative driving gears 14, 15 under operative control of the motor 4 and an appropriate reversing mechanism, such as a friction-gear power-transmission 16 in turn shiftable, as re-

quired, by aid of an actuator rod 17 Fig. 1, with

an associated pair of foot pedals 18-19 in accordance with known practice.

As illustrated, the ballast removing means conveniently, although no essentially, comprises an endless element or drag-chain 20 having integrated at 21, Fig. 4, to equally spaced links 22, scraper elements 23 preferably of angle section, see Figs. 2, 3 and 4 to best advantage; it being clearly apparent that the relatively outset flanges 24 thereof are dependent when moving over the active flight of said chain 20 during its passage through the crib 25 as later on fully set forth. The drag-device or chain 20 is trained about a grooved driving sheave 26 fast on the output shaft 27 of the power transmission reversible mechanism 16 as well as about a pair of smaller guide and tensioning pulleys 28, 29 respectively mounted, by aid of appropriate means, for free rotation on pivotal arms 30, 31 carried by bearings 32, 33 respectively rigid with the rear side and end components of the frame 5.

The chain 20 is also provided at intervals along its extent with a detachable link or links 34 whereby, when slackened, it can be readily uncoupled or released for withdrawal of that portion which extends under the rails 3, 3, between the ties 35 so that the machine can be moved from one crib 25 to another, and the chain replaced for the succeeding crib clearing operation. The output shaft 27 of the power transmission mechanism 16 is operatively coordinated, in accordance with known means such as a worm gear 36 and a drive shaft 37, as indicated by dot-and-dash lines in Fig. 1 to the motor 4; while the drag-chain 20 is continuously driven in the same direction, for example only counter-clockwise.

A spring influenced clutch 38 under control of a hand lever 39 and associated shifter means 40 is operative to couple and uncouple the grooved drive-sheave 26 to and from the out-put shaft 27.

Referring now to the means operative to adjust the working level of the drag-chain 20 by aid of the pivotal arms 30, 31, the arm 30, it will be seen is of somewhat bell-crank pattern while the arm 31 is somewhat forked whereas both of said arms embody relatively short sections 41, 42 respectively, that project inclinedly in the same angular direction, or towards the left hand as shown. It is also to be observed that the pulley 28 is located at the end of the arm 30; whereas the pulley 29 is carried by the fork end of the arm 31 which includes a curved branch 43 supporting an idler device 44, for a purpose later on again referred to. The outer ends of the pivotal arm sections 41, 42 are conveniently coordinated by rods 46, 47 and 53 which are shiftable by associated hand levers 48, 49 pivoted at 50 to the frame 5. The hand lever 48 is coupled at 51 to the rod 46; and the rod 53 is similarly attached at 55, Fig. 1, to the hand lever 49. These hand levers 48, 49 are capable of being latched together for joint movement, or of being relatively detached for independent movement and, to this end, a latching element 51 is pivotally carried on pivot pin 51a by the lever 49 and a catch lug 52 is made fast on the lever 48. Lever 48 is recessed along the line 48a to accommodate pivot pin 51a, and is free to move independently of pivot pin 51a. The pin 51a is fixed to lever 49 and to the corresponding arm of latch 51, but is simply freely received in the groove 48a in lever 48. Thus, when the latch is disengaged from catch lug 51, the lever 49 can swing about its pivot, relative to the lever 48, between limits defined on the one hand by the pin 51a and on the other hand by the closed inclined

end of latch 51, which, as shown in Figs. 1 and 4, is a substantially U-shaped member. Movement of the lever 48 when unlatched from the lever 49, to the right as viewed in Fig. 2, through a link 53 fulcrummed at 54 to the section 41 of the swingable arm 30, causes said arm 30 at the left of the machine with the associated chain guide and tensioning pulley 28 to swing outwardly and upwardly (or clockwise) and at the same time, enables corresponding movement of the swingable arm 31 outwardly and upwardly (or counterclockwise) at the right hand of the machine. Such counterclockwise movement is brought about by moving lever 49 in the direction opposite to the movement of lever 48. When both hand levers 48, 49 are latched together by the means 51, 52 and the thus combined levers are conjointly drawn to the left hand, or counter-clockwise, both of the chain guide and tensioning pulleys 28, 29 move or swing to the right or counterclockwise through corresponding arcs and effect lowering of the active flight of the drag-chain 20 from the position represented in Fig. 2 to that of Fig. 3. The operator feeds the chain 20 down by gradual manipulation of the levers 48, 49 or progressively moves them in latched connection. Obviously, when the levers 48, 49 are latched together and moved in a reverse or clockwise direction the pulleys 28, 29 will swing in clockwise direction, bringing them to the positions represented in Fig. 5 of the drawings.

The connection between the hand lever 49 and the swingable arm 31 at the right hand side of the machine, includes the rod 46 which is pivotally attached at 55 to a lateral bend 56 in said hand lever 49, while the other end of said rod passes through a guide sleeve 57 fulcrummed at 58 to the adjoining end of a plunger 59 of an automatic restoring means 70. Beyond the sleeve 57 the rod 46 is screw-threaded into a thimble 61 and secured by a lock-nut 62, see Fig. 1, which abuts, but is not connected to the adjoining end of the tubular extension 63 of guide sleeve 57. The thimble 61 is externally threaded into the adjoining end of the axially aligned tubular component 64 of the buffer means 60; whereas the remote capped end 65 of said component 64 is traversed by the rod 47 that is pivotally attached at 66 to the section 42 of the swingable arm 31. The rod 47 is sleeved or encircled in the buffer means or device 60 by a coiled spring 67, intermediate a collar 68 fast on said rod end and the inner face of the cap end 65; while said collar 68 normally abuts the confronting end of the thimble 61. A consideration of the structure just explained shows that whenever the hand lever 49 is drawn toward the operator, or the left hand side of the machine it serves to swing the chain guide and tensioning pulley 29 toward the right hand or counterclockwise under a yielding pressure exerted by the spring 67. Movement of said lever 49 in the opposite direction, or to the right, produces a reverse or clockwise movement of the pulley 29 and pivotal arm 31; also any further such movement of the hand lever 49 after relieving the spring 67 is actuated through direct contact of thimble 61 and collar 68.

From the foregoing it will also be apparent that as the levers 48 and 49 are moved toward the left hand of the machine the thimble 61 and lock nut 62 will engage the adjoining end of the guide sleeve extension 63 and shift the latter in the same direction. Such movement, through connection of the guide-sleeve 57 by the rod 59 to an auxiliary restoring device 70, which is connected at its

outer end 71 to the bracket 33, applies additional tension to the auxiliary restoring device 40. By aid of the just described means whenever the hand lever 48 alone is released from movement toward the left hand, by disengagement of the latching means 51, 52 the auxiliary restoring device 40 will function to shift the chain guide pulley 29 at the right hand side of the machine toward the left, pulley 28 remaining stationary.

The action just described will raise and slacken the chain 20 at the right hand side of the machine so that one of the detachable links 34 can be uncoupled, provided the hand lever 48 has not been moved from the position it occupies when the chain 20 is in operation. If, however, the two hand levers 48, 49 are latched together when moved, the chain 20 will be simultaneously raised at both ends and its condition of tension will not be changed, which corresponds to the action that takes place when the automatic restoring device 40 acts to raise said chain 20, as aforesaid. It is only necessary for the operator to pull both hand levers 48, 49 towards himself, or the left hand side of the machine, in order to lower the chain 20 as the ballast removing work progresses in the crib 25 being cleared.

In addition to all of the foregoing, it will be readily appreciated, that progression of our improved cribbing machine along the track rails 3, 3 in either direction is conveniently effected by the foot pedals 18, 19 through the medium of appropriate gears 73, 74, Fig. 4, and a chain drive 75, for example, from the out-put shaft 27 of the reversible transmission 16, as schematically indicated by dotted lines in said figure.

Having described the structure of our ballast-cribbing machine, as typically illustrated by the accompanying drawings, the operation thereof is as follows:

When commencing work, the drag-chain 20 is entirely removed from the machine, and the operator propels the cribber along the rails 3, 3 by aid of the motor 4, in the necessary direction, to the desired location where the work is to be done, and stops over the crib 25 to be cleared of its ballast content. It is understood that cavities 76, 76 have previously been made directly below and flanking the base flanges of said rails 3, 3. The drag chain 20 is then manually drawn lengthwise through one of the cavities 76, Fig. 2, below the selected rail 3, over the crib ballast 77, and down under the other rail 3 through the other cavity 76, thence over the superjacent guide-tensioning pulley 28, for instance, and driving sheave 26 as well as the other pulley 29, whereupon the free ends of the drag-chain 20 are drawn together and coupled into endless continuity by aid of the detachable link or links 34. It will, of course, be understood that, to facilitate application of the drag-chain 20, as explained, the latch means 51, 52 is disengaged and the hand lever 48 moved towards the right, Fig. 2, the hand lever 48 being connected at 45 to rod 46, see Fig. 2, and rod 46 being connected through the medium of buffer 60 to arm 31 at 66, causes arm 31 to swing guide wheel 29 inwards toward rail 3. Lever 49, the companion lever to 48, see Fig. 1, connected at 55 to rod 53 which in turn is connected at 54 to arm 30 when moved to left, causes arm 30 to swing guide wheel 28 inward towards rail 3. The movements of these levers, as above described, shorten the distance around and over guide wheels 28 and 29, tension wheel 44, and driving wheel 26. Next, after placing the drag chain in position as previously explained, hand levers 48 and 49 are

drawn together and latched by means of members 51, and 52 and then become operative as one lever and this action at the same time causes guide wheels 28 and 29, see Fig. 2, through the medium of rods 46 and 53 to swing outwardly from rails 3, 3 thus placing chain 20 under operating tension.

Having replaced the chain 20 and to start the same moving in a counter-clockwise direction for example only to drag ballast 77 to the right hand of Fig. 2 by means of the scrapers 23; the spring influenced clutch 38 on the output shaft 27, of the power transmission 16 is thrust into active position by aid of the hand lever 39 and shifter means 40. As the endless chain 20 travels, the latched hand levers 48, 49 are jointly moved to the left hand or are drawn by the operator stationed thereat, towards himself whereby he effects gradual depression or lowering of the active flight of said chain into the crib 25; while the machine 4, as a unit, may be moved across the full width of said crib to completely clear out, or remove, all of the ballast content 77 from the latter. When all of the ballast 77 has been removed from the crib 25 the latched hand levers 48, 49 are reversed or pushed forward by the operator to elevate the drag-chain 20, as hereinbefore explained and the latch means 51, 52 disconnected to slacken the said chain as before set forth. The chain 20 is, thereupon detached and the machine 4 moved under its own power to the next crib 25 for the succeeding cribbing operation.

From the foregoing it will be readily appreciated that by our invention we provide a simple and highly efficient cribbing machine for removing the ballast from the cribs 25 of railroad tracks; while it will be self-evident that by the continuous operation of the drag-chain, the time occupied in removing the ballast 77 is considerably reduced with a related reduction in the labor cost involved. Furthermore, by arranging a series of cribbers, as before described and shown by the drawings, in gang assembly, the saving in overhead expense may be still further reduced.

Finally our invention is not to be understood as restricted to the precise embodiment herein disclosed, since the same may be modified within the terms of the following claims without departing from the spirit and scope of said invention.

We claim:

1. Apparatus for removing ballast from the crib between adjoining ties of railroad track, comprising a wheeled truck movable along the track rails; a pair of spaced pivotal members each bearing a rotary pulley; driving means sustained by the truck intermediate the pivotal members, a flexible drag-device trained about the driving means and rotary pulleys; recoil means effective to maintain the active travel of the drag-device operatively tensioned and cushioned; pull means operative to lower the active portion of the drag-device, in opposition to the recoil means; and power actuated means with control mechanism effective to progress the drag-device in the requisite direction.

2. The invention of claim 1 wherein the spaced pivotal members are pendently carried by the wheeled truck and have the rotary pulleys proximate their lower ends; wherein one of said members is in the form of a bell-crank with a relatively short upper inclined section; and wherein the other of said pivotal members is forked and includes a correspondingly inclined section; wherein said forked member supports an idler device; and wherein coupling means connects

said pivotal members for simultaneous or independent movement.

3. The invention of claim 1 wherein the flexible drag-device is in the form of an endless chain including one or more detachable links; and wherein said chain has equally-spaced outwardly-directed scraper elements integrated thereto.

4. The invention of claim 1 wherein the recoil means for cushioning and tensioning the drag-device comprise a main and an operatively-coordinated auxiliary spring influenced movement restoring devices.

5. The invention of claim 1 wherein the pull means comprises a pair of pivotal hand levers including latch means whereby said levers are jointly movable; and wherein, when said latching means is released, one of said levers is independently movable to create a slack in the flexible drag-device, for the purpose specified.

6. The invention of claim 1 wherein the flexible drag device is trained about a driving sheave and freely rotatable guide and tensioning pulleys; and wherein said pulleys are respectively carried by operatively coordinated bell cranks having capacity for vertical rotary movement.

7. In apparatus for removing ballast from the cribs between the ties of a railroad track, a wheeled truck; a flexible endless drag element adapted to be passed transversely of the track over the road bed and through pre-cleared spaces directly beneath the respective track rails; end guide wheels about which the drag element is trained; pivotal suspension arms supporting the guide wheels from the truck outward of the rails; means for driving the drag element; cushioning means influential upon the arms to allow upward yielding of the active portion of the drag element between the rails during removal of the ballast; means for concurrently moving the arms about their pivots to raise and lower the drag element for regulating the depth to which the ballast is removed; and means for taking up any excess slack occurring in the drag element as the arms are so moved.

8. Apparatus for removing ballast from between adjacent track ties below the rails in a road bed comprising a carriage movable along the track, spaced suspension arms pivoted to opposite sides of said carriage, guide members mounted on said arms with capacity to swing up and down about said pivots in a path that extends outside said rails, driving means on said carriage, a flexible drag element trained about the driving means and guide members and thereby passed transversely of the track over the road bed, drag element engaging means mounted on one of said arms with capacity to swing toward and from said drag element, and resilient means carried on the carriage influential upon one of said arms to swing said arm about its pivot and

force said engaging means against said drag element and thereby tension said drag element.

9. Apparatus for removing ballast from between adjacent track ties in a road bed comprising a carriage movable along the track, spaced suspension arms pivoted to said carriage, guide members mounted on said suspension arms with capacity to swing about said pivots, driving means on said carriage, a flexible drag element having ends provided with link means, said drag element being arranged to be trained about the driving means and also trained about the guide members and passed transversely of the track over the road bed to form a closed circuit when said ends are linked together, means for concurrently moving said suspension arms about their pivots to raise and lower the drag element for regulating the depth to which the ballast is removed, an idler element carried by one of said arms, and resilient means carried by the carriage and arranged to urge the idler element against the drag element.

10. In apparatus for removing ballast from the cribs between ties of a railroad track, a wheeled truck; a flexible endless drag element adapted to be passed transversely of the track over the road bed and through pre-cleared spaces directly beneath the respective track rails; end guide wheels carried by said truck about which the drag element is trained; movable means also carried by said truck and supporting the guide wheels from the truck outward of the rails; means on said truck for driving the drag element; and cushioning means carried by said truck and influential upon the guide wheel supporting means to allow upward yielding of the active portion of the drag element between the rails during removal of the ballast, said drag element being composed of separable sections provided with detachable link means to permit reeving of said drag element beneath the track rails; and means operatively connected to the guide wheel supporting means whereby the guide wheel supporting means can be moved in opposition to the influence of the cushioning means to slack the drag element and thereby facilitate its placement in preparation for each cribbing operation.
